CHAIN MAKING MACHINE

Emil Mueller, Cranston, R. I., assignor to Speidel Chain Co., Providence, R. I., a firm composed of Frederic Speidel and Eugen Speidel

Application May 15, 1931, Serial No. 537,642

16 Claims. (Cl. 59—15)

This invention relates to a chain making machine and has for its object to provide a construction which will mechanically form from a strip of sheet stock articulate links and join them together, in forming a chain of any desired length.

Another object of the invention is the provision of a construction by which the links as formed may be in full view of the operator of the machine that any flaws might be immediately detected.

Another object of the invention is the provision of an anvil acting from above the link against which the closing former presses the link in closing the same about the previously formed link thus permitting the forming of the link to be better viewed by the operator.

Another object of the invention is the feeding of the formed link laterally and in substantially the plane of the fed strip to be observed by the operator rather than dropped through a tube or the like as has been customary.

Another object of the machine is the provision of a construction by which a desired design on the chain may be formed more sharply than from dies or the like ornamentation.

Another object of the invention is the provision of a construction by which the ornamentation is marked in the work partially by pressure and then finished by striking the tool with a hammer.

A still further object of the invention is a provision of an improved feeding mechanism which will be anti-frictionally guided and pressed into gripping position.

A still further object of the invention is the provision of a feeding means so located as to pull the strip of work into the machine and through the first part of the forming operations until the strip is bent and stiffened and from this point on pushing the strip through the machine.

With these and other objects and advantageous features in view, the invention consists of a novel arrangement of parts more fully disclosed in the detailed description following, in conjunction with the accompanying drawings, and more particularly set forth in the appended claims.

Fig. 1 is a front elevation of the machine. Fig. 2 is an end view of the machine as a whole with the pulley removed or a section on line 2—2 of Fig. 1.

Fig. 3 is a top plan view of a portion of the machine to show the feeding of the strip and the cam lever for the anvil with the remaining por-

tions of the machine removed for the sake of clearness.

Fig. 4 is a section on line 4—4 of Fig. 3.

Fig. 5 is a perspective view of a strip showing the different formations which it takes in passing through the machine.

Fig. 6 is a sectional view on line 6—6 of Fig. 1.

Figures 7, 8 and 9 are sectional views on enlarged scale through the chain and link in three different positions in the operation of the parts.

Fig. 10 is a section on line 10—10 of Fig. 1.

Fig. 11 is a section on line 11—11 of Fig. 1.

In the making of link chains from sheet stock it is desirable that these be made mechanically in automatic machines whereby a strip of sheet stock blank may be fed into the machine and the finished chain with engraving thereon emerge from the machine. And in order that the engraving may be more distinct I employ a striking or hammer mechanism on the pressure tools for

impressing this ornamentation which causes the ornamentation to have a sharper hue and stand out more distinctly. Also the stock when fed into the machine is more or less flexible and may be easily bent and therefore instead of pushing this stock into the machine which might cause buckling thereof I pull the stock into the machine until the first few operations are performed and the stock is bent to stiffen it after which I push the stock through the remaining operations in the

machine without fear of bending the same, and my feeding operation is such that the pulling blocks ride between rollers and are thus supported from the bottom as well as pressed from the top by anti-friction means. I also find it desirable to

arrange the operating mechanism so that the formed link may be viewed as united to the chain to detect any imperfections in the link, so that should a flaw occur the machine may be immediately stopped and a new link caused to replace

the imperfect one without wasting several links of the chain which might otherwise be necessary; and the following is a detailed description of the present embodiment of this invention illustrating the preferred means by which these advantageous

results may be accomplished.

With reference to the drawings, Fig. 5 illustrates somewhat diagrammatically a blank strip and the several operations in forming a chain in the shape which it obtains on passing through the machine. Thus it will be observed that the plain ribbon band 15 in suitable reel form is fed into the machine and in the first operation opening 16 and notch 17 are cut therein as well as

ornamentation 18 impressed thereon. At the sec-

100

105

110

ond operation the stock is bent both to offset a part 19 of the body and bend the edge 20 of the tongue 21. The next operation of the machine bends the tongue 21 downwardly to form a right angle fold 22 after which the link is severed as at 23 and connected to the end link 24 of the chain which receives the tongue 21 through its opening 16 after which the tongue is bent into closed position to complete the operations thereon as illustrated in Figures 7, 8 and 9, and then it is moved into a position to receive the next link formed and so on.

Referring to Fig. 1, the operation of piercing the opening 16, cutting the notch 17 and ornamenting as at 18 takes place between the lower die 25 and the upper die 26 suitably moved by a plunger or reciprocating rod 27, rocker arm 28 pivoted as at 29 and cam 30 connected to the rocker arm 28 by a strip 31, cam 30 being moved about cam shaft 32 as is disclosed in Fig. 11. The first bending operation takes place between a lower tool 33 and an upper tool 34. The second bending operation takes place between lower tool 35 and upper tool 36 while the severing takes place between cutters 37 and 38. Between the two bending operations the lower feed block 39 and the upper feed block 40 is placed to suitably feed the stock in the machine.

Each of the bending tools, as well as the cutters and feed blocks are actuated by vertically moving plungers or reciprocating rods designated 41, 42, 43 and 44, and are moved in one direction by means of similar springs which I will designate generally as 45. Also the rocker arms and cams which actuate these plungers are all of identical construction and it will suffice for description to refer to Fig. 10 showing the plunger 43 for the second bending operation with its rocker arm 46 mounted upon shaft 29 and actuated by a suitable cam which in this instance is 47 engaging roller 48 mounted upon the end of the arm 46. It will of course be understood that the cams for actuating each of the rocker arms are of different shape to cause the desired timing coordination of the different working parts.

The feeding occurs between previously mentioned blocks 39 and 40 (note particularly Figures 3 and 4) which are moved apart by spring 49. The lower block 39 is carried on shaft 52 and rests upon anti-friction roll 50 mounted in the bottom plate 51 of the machine and shaft 52 is slidably mounted in bearing 53 and moved in one direction by means of spring 54 engaging the bearing 53 and collar 55 secured on the shaft 52. The shaft is moved in the opposite direction by means of a rocker arm 56 pivoted as at 57 to engage the adjustable set screw 58 in the end 59 of the shaft 52 and which is rocked about shaft 57 by means of the first cam 60 illustrated in dotted lines in Fig. 2 and in full lines in Fig. 1 which cam 60 is mounted on the cam shaft 32 heretofore mentioned. The feeding of the strip takes place when suitable downward movement on the plunger 42 causes pressure on the upper block 40 through the anti-friction roll 61 and the shaft 52 bodily moves the blocks to feed the strip forward. At the end of the stroke the pressure upon the lever rod 42 releases and the spring 49 separates blocks 39 and 40, and a return movement of the blocks occurs by reason of spring 54 for another bite or hold upon the strip.

The severing tool 62 in moving to sever the partially formed link as illustrated at the right hand end of Fig. 5 also moves a member 63 acting as an anvil into engagement with the

work and at a time just prior to this severing, jaws 64 and 65 grip the partially formed link and hold it in a position illustrated in Fig. 7 whereby the end link 66 of the formed chain 67 is caused to rise by means of the inclined support 68 to cause the opening 16 in this end link to pass over the tongue 21 after which the former 69 continues its upward movement and closes the tongue 21 of the link as illustrated in Fig. 8. This operation occurs through the action of rock lever 70 pivoted at 71 and operated by means of a rod 72 having a roll 73 on the end thereof and engaging cam 74 which forces the carrier designated generally 75 upwardly. The carrier has mounted therein a slide 76 at the upper end of which is the inclined support portion 68. This slide carries a pin 77 for engagement with a stop 78 fixed on the frame of the machine and limits the movement of slide 76 of the carrier which is yieldingly supported by spring 81 mounted in member 80 of the slide and through yielding of spring 81 the carrier continues to move upwardly and cause the former 69 mounted thereon to fold or close the tongue of the link.

A pawl 82 is pressed by spring 103 to bind 100 the chain against the inclined support surface of the carrier 68 during its movement and while the link is being formed. The cutter and anvil 62 carry arm 83 having a pin adjacent its end for engagement with the pin 84 on the clamp 105 82 mounted on the support 68 to lift the clamp and release the chain and permit its forward movement by the jaws 64 and 65. These jaws are mounted upon the carriage 88 which is moved in one direction by spring 92 and moved forward 110 or in the other direction by lever 89 engaging an adjustable abutment 90, the lever being actuated by cam 91 whereby the formed portion of the chain is moved to position it for the reception of a new link. The jaws are closed by spring 115 87 and released by means of cam 86 acting on roll 85 at the end of extension 84 connected to the upper jaw.

In order that the design impressed by the tools may be more sharply brought out, I provide a 120 hammer 93 at the end of a lever arm 94 pivoted at 95 to the frame portion 96 of the machine. The end portion 97 of said lever engages the cam 98 upon the cam shaft 32 which holds the hammer in raised position as illustrated in Fig. 125 2 and permits this hammer to drop assisted by spring 99, into contact with the hardened striker member 100 of the slide 27 whereby the design which is impressed in the work by the forming tools 25 and 26 is made more distinct.

I claim:

1. In a chain making machine, means for feeding a strip of sheet stock, means for partially bending a link, means for causing the bent portion of said link to be threaded through the 135 previously formed link at a point in line with the strip, and means subsequently operating in a vertical path for closing said portion of the partially formed link.

2. In a chain making machine, means for feeding a strip of sheet stock, means for partially forming a link, means for causing the same to be threaded through the previously formed link, an anvil member, means for moving the anvil over the partially formed link, and means subsequently moving upwardly for closing the partially formed link by forcing it against the anvil member.

3. In a chain making machine, means for feeding a strip of sheet stock in substantially a hori- 150

- zontal plane, means for partially forming a link, means for causing the same to be threaded through a previously formed link at a point in line with the strip of sheet stock, means for completing the formation of the partially formed link, and means for feeding the last formed link laterally with respect to the movement of the strip and in substantially a horizontal plane. 5 80
4. In a chain making machine, means for feeding a strip of sheet stock in substantially a horizontal plane, means for partially forming a link, means for causing the same to be threaded through a previously formed link, means for completing the formation of the partially formed link, and means for feeding the last formed link laterally with respect to the movement of the strip and in substantially the plane of the strip being fed. 10 85
5. In a chain making machine, means for feeding a strip of sheet stock, means for partially forming a link, means for lifting a portion of the chain and the previously formed link to thread therethrough the partially formed link and a portion of said means continuing its movement to close the partly formed link. 15 90
6. In a chain making machine, means for feeding a strip of sheet stock means for partially forming a link, means for lifting and clamping thereto a portion of the chain and means for releasing said chain and moving it relative to said lifting means. 20 95
7. In a chain making machine, means for feeding a strip of sheet stock, means for partially forming a link, means for lifting and clamping thereto a portion of the chain and means for releasing said chain and moving it relative to said lifting means and in substantially the plane of the fed stock. 25 100
8. In a chain making machine, two separate means for bending sheet stock, means for feeding a strip of sheet stock, means for cutting the strip stock into desired shape, said feeding means located between said bending means to pull the stock through the first bending operation on the machine. 30 105
9. In a chain making machine, means for feeding a strip of sheet stock, means for cutting the strip stock into desired shape, means for partially bending the strip stock, means for further bending and operating on the strip stock said feeding means being located between said bending means to push the strip to the second bending operation whereby the stock is pulled in its more flexible state and pushed after being stiffened by bending. 35 110
10. In a chain making machine, means for feeding a strip of sheet stock means for ornamenting said strip comprising means for moving tools into engagement with the strip and subsequently striking the tools with a blow from a hammer or the like to more sharply impress the ornamentation of the tool therein. 40 115
11. In a chain making machine, means for cutting a strip into suitable shape, means for partially bending said strip, feeding means for pulling said strip through said means and pushing it through subsequent operations of the machine, means for further bending said strip, and means for severing the partially formed link and attaching it to a chain. 45 120
12. In a chain making machine, means for cutting a strip into suitable shape, means for partially bending said strip, feeding means for pulling said strip through said means and pushing it through the subsequent operation of the machine, means for further bending said strip, and means for severing the partially formed link and at the same time gripping and holding it and means for moving the formed chain to attach the gripped link thereto. 50 125
13. In a chain making machine means for cutting a strip into suitable shape, means for partially bending said strip, feeding means for pulling said strip through said means and pushing it through the subsequent operation of the machine, means for further bending said strip, and means for severing the partially formed link and at the same time gripping and holding it and means for moving the formed chain to attach the gripped link thereto and means for causing said gripping means to feed the last formed link and chain into a new position, and means for manipulating said link from this new position for the reception of the next link. 55 130
14. A chain making machine means for advancing a strip of sheet stock in substantially a horizontal plane, means for forming links from said sheet stock, means for attaching said links to a chain, and means for advancing the last formed and attached link in the chain laterally with respect to the movement of the strip, and in substantially the same plane as the sheet stock fed and prior to the attaching of the next link to the chain. 60 135
15. A chain making machine including means for advancing a strip of sheet stock in substantially a horizontal plane to be subsequently formed into a chain, second means for holding the chain in position when an adjoining link formed from said advancing strip is connected thereto, and means releasing the second means and means for advancing the last connected link in the chain laterally with respect to the movement of the strip and in substantially the same horizontal plane as the strip of sheet stock fed and prior to the attaching of the next link to the chain. 65 140
16. A chain making machine, means for feeding a partially formed link in substantially a horizontal plane, means for attaching said partially formed link to a chain, and means for advancing the last attached link in the chain laterally with respect to the direction of movement of the partially formed link, and in substantially a horizontal plane. 70 145

EMIL MUELLER.
